UNITED STATES PATENT OFFICE.

WILLIAM McCALLUM, OF YONKERS, NEW YORK, ASSIGNOR TO JOSEPH WILD & CO., OF NEW YORK CITY.

DESIGN FOR A CARPET-PATTERN.

Specification forming part of Design No. 5,551, dated February 20, 1872.

Specification describing a new and original Design for Carpet, invented by WILLIAM McCALLUM, of Yonkers, in the county of Westchester and State of New York.

The accompanying photographic illustration fully represents my new design.

This invention relates to a new design of rosette, ornamental octagon, and floral scroll or filling, to be employed in the decoration of a carpet.

The rosette A is decorated at the prominent points with small shields, a a, and contains in the middle a quatre-foil, b, within which a bouquet, d, is displayed. The figure B is of octagonal form, with alternate straight and curved lines, and a scroll in the middle. The floral scroll C is made of fantastic flowers, leaves, tendrils, and tufts or bunches, as shown.

I claim as my invention—

1. The design of the rosette A, as shown.
2. The design of the octagonal figure B, as shown.
3. The design of the floral scroll C, as shown.
4. The design for a carpet containing the figures A B and the scroll C, as shown.

WILLIAM McCALLUM.
